UNITED STATES PATENT OFFICE.

RALPH RAGAN, OF ATLANTA, GEORGIA.

EXPLOSIVE-ENGINE.

1,139,578.

Specification of Letters Patent. Patented May 18, 1915.

Application filed November 14, 1912. Serial No. 731,397.

To all whom it may concern:

Be it known that I, RALPH RAGAN, a citizen of the United States; residing at Atlanta, in the county of Fulton and State of Georgia, have invented a new and useful Explosive-Engine, of which the following is a specification.

The present invention relates to an improvement in explosive engines, the present structure being a refinement of the structure set forth in applicant's co-pending application filed July 24, 1911, Serial No. 640,267, and the primary object of the present invention being the provision of a single valve interposed between the carbureted air compressing cylinder and the explosive cylinder for controlling the supply of carbureted air to the explosive cylinder and the exhaust of the burnt gases therefrom.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings—Figure 1 is a side elevation of an explosive engine made according to and embodying the present invention, one of the power cylinders and carbureted air supplying cylinders being shown in section.

Fig. 2 is a section taken on lines 2—2 of Figs. 1 and 5. Fig. 3 is a section taken on line 3—3 of Fig. 1. Fig. 4 is a section taken on line 4—4 of Fig. 1. Fig. 5 is a horizontal section through the engine taken on line 5—5 of

Fig. 2. Fig. 6 is a section taken on line 6—6 of Fig. 1 illustrating the connection of the carbureted air supplying cylinder with the carbureted air supplying manifold of the engine.

Referring to the drawings, the numeral 1 designates the base which is provided with the fixed upwardly inclined and converging walls 2 which are connected together by the bridging piece 2', there being formed upon the inner face of the wall in spaced relation and in co-operating pairs, the frames 3, which carry the guides 4, the purpose of which will presently appear.

Sealing the base 1 is the curved plate 5 which constitutes with the adjacent portion

of the base, the lubricant containing compartment and crank case of the engine.

The crank shaft 6 is properly journaled within the base and has connected thereto, the piston rod 7 which has its upper end connected to the cross head 8. This cross head 8 is of peculiar construction and is made in separable parts, the outer portion 9 of which is in engagement with the respective guides 4 being held with the main portion of the cross head by means of the adjusting device 10, said adjusting device being so positioned as to permit of the adjustment of the wedge section 9 due to the wear thereof in its action upon the guides 4.

Connected to the cross head 8 and projecting upwardly therefrom is a cylindrical piston rod 11 which projects through the bridging plate 2' and carries upon its upper end, the power piston 12, which as shown is provided with the oppositely disposed baffle plates 13—13'. This power piston 12 is mounted for reciprocation within the power cylinder 14 and as shown divides the cylinder into the two explosive compartments C and C'.

Provided in the wall of the cylinder 14 intermediate of the ends thereof, are the two intake ports 16, and the two exhaust ports 16', the vertical length of the exhaust ports 16' being slightly greater than the intake ports 16, the purpose of which will presently appear.

Led into the respective intake ports of the cylinder is the goose neck portion 17 of the intake manifold 18 which is in communication with the vertical manifold 18' connected with the carburetor, or other carbureted air supplying device (not shown). The portion 18^a of the intake manifold is slightly tapered for the reception of the frusto-conical carbureted air supplying valve 19, the detail of which will be set forth later on.

Connected to the crank shaft is a connecting rod 20 which is connected to a cross head 21 similar to the cross head 8, while connected to this cross head is a cylindrical piston rod 22 which is also slidably mounted through the bridging plate 2' and carries upon its upper end, the carbureted air compressing and supplying piston 23 which is mounted for reciprocation within the carbureted air supplying cylinder or chamber 24. This chamber is provided with the conduits 25 and 26, both of which are in com-

munication with the intake manifold 18^a at diametrically opposite points and adjacent to the frusto-conical valve 19.

In the form of engine herein shown, two 5 frusto-conical valves 19 are provided and are normally held resiliently off their seat by means of the spring 27 mounted upon the sheet shaft 28 and disposed between and concentrically of the valves 19 while the 10 bushing 29 of each valve is keyed for rotation upon and with the shaft 28 and also with the operating shaft 30 which is extended forwardly through the bearing sleeve 31 carried by the goose neck portion 15 17 of the intake manifold.

The frusto-conical valve is provided with the angularly disposed partition 32 which divides the valve into two compartments one leading into each of the respective compartments, and through the wall of the valve are the respective ports 33-34, said ports being disposed for registration with the intake manifold 18^a for conducting the carbureted air into the respective chambers 25 of the compressing cylinder 24 and also for directing the compressed carbureted air from the respective chambers of the compression cylinder 24 to the intake ports 16 of the cylinder 14, the position of the power 30 piston 12 determining which chamber of the power cylinder 14 will receive the charge. Thus when the power piston 12 is in the 35 position as shown in Fig. 2, the charge is being exhausted from the chamber C' through the ports 16', while the piston 23 is forcing a charge of carbureted air through the port 16 into the chamber C, said compressed charge being propelled against the baffle plate 13' so as to assist in 40 scavenging the chamber and supplying the necessary charge of carbureted air thereto for the compression and explosive stroke, as illustrated by the position of the piston 12 in the chamber C' in Fig. 2. It will thus 45 be seen that with this construction and arrangement of the valves 19, a single valve will control the admission of the carbureted air from the manifold 18 into either one of the conduits 25 and 26 and consequently 50 into the two chambers formed by the piston 23 in the carbureted air compression cylinder 24, and also at the same time lead the charge from the respective conduits 25 or 26 in through the goose neck portion 17 to the power cylinder 14.

The piston 12 acts as the exhaust valve controlling the exhausting of the burnt charges through the ports 16' and finally into the exhaust manifold 35.

In order to operate the valve actuating 60 rod 30 in time with the power piston 12 and carbureted air piston 23, the gear 36 is keyed upon the crank shaft and is in mesh with a gear 37 keyed upon the lower end of the vertical shaft 38, said shaft 38 being

journaled in the bearings 39-39' within the crank case and the upper bearings 40 and 41, as clearly shown in Fig. 3. Keyed upon the shaft 38 adjacent its upper end is a pinion 42, which meshes at all times with 70 a pinion 43, said pinion 43 being keyed upon the shaft 30 and thus forming the means whereby the rotation of the crank shaft will rotate the vertical shaft 38 and consequently the valves 19. 75

Disposed upon and within the reduced end of the goose neck 17 is a spider 44, which acts as a journal bearing for the shaft 30 and also as a means against which the lock and adjusting nut 45 abuts to regulate the setting of the valves 19 within the tapered portion of the manifold. 80

Formed at the lowest portion of the crank case, are the depressions or cups 46, there being two in this instance, and disposed 85 concentrically of and within each of these cups is the oil directing and sediment retaining pipe 47, which is disposed within the short cylindrical casing or coupling 48, which has led thereaway from the lower 90 feed or circulating pipe 49, which leads into the rotary pump casing 50, the elements of the pump being operably connected to and at the lower end of the vertical shaft 38. Thus it will be seen that the pump through 95 the pipes 49 and 51, the manifold 52 and the pipe 71 and tube 73, as will presently appear, is a circulator for the lubricant supplying system and also the carbureted air supplying valves are operated from the sprocket gear 36 and the shaft 38. 100

From the pump casing is a conducting pipe 51, which as shown is in communication with the lubricant manifold 52 disposed longitudinally of the engine and adjacent to the bridging plate 2', thereof, the same having disposed therewithin the tubular distributing portion 53, which as shown is provided with a port 54 and into which lubricant is supplied to the power piston rod 14 and the port 55, whereby lubricant is supplied to the carbureted air supplying piston rod 22. 110

It is desirable that only a limited amount of lubricant be supplied to the power piston rod 14, and primarily during the down stroke of the piston 12, and in order to accomplish this, disposed concentrically of and rotatable within the tubular distributing portion 53, is a shaft 56 having the two ports 57 and 58 disposed for registration respectively with the ports 54 and 59 and 60 and 61. The port 59 leads to the stuffing box 62' about the power piston rod 14 and below the bridging plate 2', while the port 60 leads thereaway from so that the desired circulation of the lubricant within the stuffing box 62' is provided, the lubricant being led through the ports 60, 58 and 61 to the port 63 and through the pipe 71 and the 120 130

casing 73 so that the lubricant is led into the base of the engine and also against the guides 4 to properly lubricate the cross head 8.

5 It will be seen that as the oil or lubricant is within the crank case and has entered the pipe 49, the engine being operated explosively, operates the rotary pump 50 so that lubricant is drawn into the casing thereof and forced into the pipe 51 which directs such lubricant into the lubricant manifold 52 longitudinally of the engine. From there, the lubricant being under pressure, is directed through the apertures 55 10 into the tubular distributor 53, to properly lubricate a rotary distributing member 56 and at the same time direct such lubricant as is necessary through the port 64 so that the stuffing box 65 is properly lubricated. Other lubricant is led from the manifold 52 15 through the port 54, so that when the port 57 of the distributor 56 alines therewith, the lubricant will be directed through the port 57 into the port 59 and consequently into the stuffing box 62', the circulation continuing therethrough and out of the port 60 to the alined port 58 of the distributing member 56 into and through the port 61 to the tube 6 (Fig. 2), that directs the oil to the upper portion of the guide 4 to assist in oiling the cross head 8. As the return conduit 71 is in communication with the manifold 52 at the opposite end from the introduction of the pipe 51 thereto, a continuous circulation of the lubricant within the manifold 52 is accorded, the pipe 71 leading the greater portion of the flow of lubricant into the upper end of the casing 73, where it is directed again into the base of the engine.

20 The stuffing box 62' is provided with a plurality of packing rings 63' which are so disposed as to permit of the feeding of the necessary lubricant to the rod 11 and thus prevent the exploding gases from affecting the same, the same providing a means whereby the necessary film of oil will be supplied intermittently to the rod 11 and without any loss of power either upon the explosion or compression stroke.

25 The port 64 leads from the tubular conduit 53 adjacent to the reduced portion of the valve 56, and a continuous supply of oil is fed to the stuffing box 65 around the cylindrical piston rod 22, the adjustable packing 56 therewith providing a means whereby the necessary lubricating oil is supplied within the cylinder 24 through the lower conduit 26 into the manifold 18, and through the goose neck portion 17 and the intake port 16 of the cylinder 14. By this means the cylinder 14 and its power piston 12 are properly lubricated.

30 In order to properly rotate the valve 56 in timed relation to the pistons 12 and 23 65 so that the ports 57 and 58 are successively

or alternately brought into or out of communication with one another through the valve 56 as desired, a sleeve 67 is keyed upon the shaft 38 and carries a small bevel pinion 68 which is in mesh at all times with the bevel pinion 69 keyed upon the outer end of the valve shaft 56', thus providing a means whereby the rotation of the shaft 38 will actuate the valve 56.

Led from the opposite end of the oil manifold 52 and connected to the tap 70 thereof, is a return conduit 71 which has disposed therein an oil or sight gage, (not shown) the conduit leading into the tap 72 at the upper end of the casing 73 which surrounds the shaft 38 and acts as a conducting medium to return the lubricant into the lower portion of the crank case, all as clearly shown in Fig. 3. The large bevel gear 68', is geared to operate the armature of the ignition magneto M.

In order that the various frictional parts and the cylinders of the engine may be water cooled, the pump 76 is controlled from the gear 36 which is mounted upon the crank shaft. The gear 74 is keyed upon the flexible shaft 75 which controls the rotary pump 76 disposed within the casing 77. The lead in conduit 77' to which the water is supplied by any source is connected to the casing 77, the conduit 78 formed within the base of the engine and connected to the casing 77 leads into the jacket 79 below the bridging plate 2' and into the stuffing box jackets 79'. From the jacket 79 is led a coupling 80, which forms the conduit to lead the water into the lower portion of the water jacket 81 of the cylinder 14, there being led from the upper end thereof, a conduit 82 which is led to the usual radiator (which is not shown) and finally back to the inlet conduit 77'.

It will thus be seen that the gear 36 upon the crank shaft forms a medium for operating the valves 19, the lubricating pump 50, the distributing valve 56, also the water circulating pump 76, and the magneto M.

From the foregoing description taken in connection with the drawings it is evident that with an engine constructed according to and embodying the present invention, that the various frictional parts are properly cooled and lubricated, and that the timing of the spark plugs disposed within the sockets 15-15' may be readily adjusted and controlled through the shaft 38, so that the explosive charges within the chambers C-C' are exploded at the highest point of compression so that there are two explosions every two strokes of the power piston 12.

What is claimed is:

1. An explosive engine, including a base a crank shaft mounted therein, a carbureted air compressing and supplying cylinder, a piston mounted therein and operably

- connected to the crank shaft, a power cylinder, a power piston mounted therein and operably connected to the crank shaft, an intake manifold, said power cylinder being 5 provided with intake and exhaust ports intermediate of its ends, the intake port being in communication with the intake manifold, two oppositely disposed pipes led from the intake manifold to the respective ends of the 10 air compressing and supplying cylinder, a valve mounted for rotation within the manifold and divided into two oppositely open ended chambers, each of said chambers being provided with a port for registration 15 with the pipes of the carbureted air supplying and compressing cylinder, and means for operably connecting the valve to the crank shaft.
2. An explosive engine, having a power cylinder, and a carbureted air compressing and supplying cylinder, an intake manifold in communication with the intake port of the power cylinder, two pipes leading from the intake manifold to the respective ends of 25 the air compressing and supplying cylinder, a valve mounted for rotation within the intake manifold adjacent the point of connection of the two pipes therewith, said valve being divided into two open ended chambers, 30 each of said chambers being provided with a port for registration with the pipes of the carbureted air supplying and compressing cylinder.
3. An explosive engine, including a base, 35 a crank shaft mounted therein, a carbureted air compressing and supplying cylinder, a piston mounted therein and operably connected to the crank shaft, a power cylinder, a piston mounted in the power cylinder and 40 operably connected to the crank shaft, an intake manifold disposed longitudinally of the engine, said power cylinder being provided with intake and exhaust ports intermediate of its ends, the intake port being in 45 communication with the intake manifold, two oppositely disposed pipes led from the intake manifold to the respective ends of the air compressing and supplying cylinder, the portion of the manifold adjacent to said 50 pipes being enlarged, a frusto-conical valve mounted for rotation within the enlarged portion of the manifold and divided into two oppositely open ended chambers, each of said 55 chambers being provided with a port for registration with the pipes of the carbureted air supplying and compression cylinder, and means for operably connecting the valve to the crank shaft.
4. An explosive engine, including a base, 60 a crank shaft mounted therein, a carbureted
- air compressing and supplying cylinder, a piston mounted therein and operably connected to the crank shaft, a power cylinder, a piston mounted in the power cylinder and operably connected to the crank shaft, an intake manifold disposed longitudinally of the engine, said power cylinder being provided with intake and exhaust ports intermediate of its ends, the intake port being in communication with the intake manifold, two oppositely disposed pipes led from the intake manifold to the respective ends of the air compressing and supplying cylinder, the portion of the manifold adjacent to said pipes being enlarged, a frusto-conical valve mounted for rotation within the enlarged portion of the manifold and divided into two oppositely open ended chambers, each of said chambers being provided with a port for registration with the pipes of the carbureted air supplying and compressing cylinder, and means for operably connecting the valve to the crank shaft.
5. An explosive engine, including a base, a crank shaft mounted therein, a carbureted air compressing and supplying cylinder, a piston mounted therein and operably connected to the crank shaft, a power cylinder, a piston mounted in the power cylinder and operably connected to the crank shaft, an intake manifold disposed longitudinally of the engine, said power cylinder being provided with intake and exhaust ports intermediate of its ends, the intake port being in communication with the intake manifold, two oppositely disposed pipes led from the intake manifold to the respective ends of the air compressing and supplying cylinder, the portion of the manifold adjacent to said pipes being enlarged, a frusto-conical valve mounted for rotation within the enlarged portion of the manifold and divided into two oppositely open ended chambers, each of said chambers being provided with a port for registration with the pipes of the carbureted air supplying and compressing cylinder, and means for operably connecting the valve to the crank shaft.

In testimony that I claim the foregoing as my own, I have hereto affixed my signature in the presence of two witnesses.

RALPH RAGAN.
